UNITED STATES PATENT OFFICE

152,947

DESIGN FOR A WALLET OR SIMILAR ARTICLE

Frank George Dobbs, Kew Gardens, and Stephan H. Dobbs, New York, N. Y.

Application January 17, 1948, Serial No. 143,847

Term of patent 14 years

(Cl. D87—3)

To all whom it may concern:

Be it known that we, Frank G. Dobbs and Stephan H. Dobbs, both citizens of the United States of America, residing at Kew Gardens, Queens County, New York State, and New York City, New York County, New York State, respectively, have invented a new, original, and ornamental Design for a Wallet or Similar Article, of which the following is a specification, reference being had to the accompanying drawing, forming part thereof.

In the drawing,

Fig. 1 is a plan view of a wallet or similar article showing our new design, in unfolded position.

Fig. 2 is a similar view in folded position.

We claim:

The ornamental design for a wallet or similar article, as shown.

FRANK GEORGE DOBBS.
STEPHAN H. DOBBS.
